Des. 208,549
Patented Sept. 12, 1967

208,549

TESTER FOR ELECTRIC METER SOCKETS

William L. Hoss, 3016 Lunds Lane,
West Palm Beach, Fla. 33405

Filed Mar. 28, 1966, Ser. No. 1,647

Term of patent 14 years

(Cl. D26—1)

FIG. 1

FIG. 3

FIG. 2

FIG. 4

FIG. 1 is a front elevation of a tester for electric meter sockets, showing my new design.

FIG. 2 is a rear elevation thereof.

FIG. 3 is a side elevation thereof.

FIG. 4 is a top view thereof.

The sides not shown in FIGS. 3 and 4 are the same as the corresponding sides shown.

The dominant features of the design are shown in full lines.

I claim:

The ornamental design for a tester for electric meter sockets, as shown and described.
